(57) **CLAIM**

The ornamental design for medical equipment, as shown and described.

DESCRIPTION

FIG. 1 is a perspective view of medical equipment showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof; and,

FIG. 8 is an enlarged perspective view at the distal end of the medical equipment showing our new design.

The broken lines showing portions of the medical equipment are included for illustrating environmental structure and form no part of the claimed design.
